CAB LAMP

Frederick W. Blanchard, Hampstead, Quebec,
Canada, assignor to T. McAvity & Sons Limited, Montreal, Quebec, Canada

Application December 14, 1942, Serial No. 468,991

1 Claim. (Cl. 240—7.1)

This invention relates to light projecting lamps for locomotive cabs and the object is to provide a generally improved lamp of the type disclosed in my prior patent No. 1,947,377 granted Feb. 13, 1934.

The lamp disclosed in the above mentioned patent is adapted to be arranged in the upper rear portion of the cab and is provided with a series of light emitting openings including a bottom opening for illuminating the floor and rear portion of the cab and a plurality of front openings for illuminating the various indicating instruments, the size and location of said front openings being carefully predetermined to project concentrated beams of light onto the indicating instruments in such manner as to avoid excessive illumination or objectionable glare from the back head of the locomotive boiler or from other light reflecting surfaces outside the areas actually occupied by the indicating instruments. Such lamps have now been used extensively and have proven very satisfactory in service.

One of the improvements contemplated by the present invention is the provision of means for increasing the efficiency of the lamp by eliminating or substantially reducing the amount of light which is reflected through the front openings of the lamp from inside wall surfaces of the lamp casing located between said openings and the light source. This is accomplished by the provision of a light intercepting and controlling diaphragm which is arranged in front of and relatively close to the light source. This diaphragm is provided with a central opening, the area and location of which is such that substantially all the light rays passing therethrough are directed toward the front cover of the lamp casing without falling on and being reflected by the inner wall portions of the lamp casing which lie between the cover and the diaphragm. This diaphragm also has the effect of reducing the extent to which the interior of the cab is illuminated by light projected through the front openings of the lamp casing without objectionably diminishing the desired illumination of the instruments mounted on the back head of the boiler. This reduction in illumination due to light reflected from portions of the lamp casing lying between the light source and the front openings is very desirable under ordinary conditions but is particularly useful in the case of a locomotive which is being operated under air raid black-out conditions.

Another feature of the invention consists in constructing the light intercepting and control-

ling diaphragm so that light filters may be arranged over the central opening thereof so as to still further reduce the extent to which the interior of the cab is illuminated by scattered light which would be objectionable under black-out conditions.

A still further feature of the invention consists in the provision of a lamp in which the light intercepting and controlling diaphragm is fitted 10 with a light filter which absorbs all except the ultra-violet light rays coming from the light source. When such a filter is used the hands and calibration of the indicating instruments may be painted with a substance which, when illuminated by ultra-violet light rays, is made luminescent. This enables the indicating instruments to be rendered visible with very little, if any, illumination of the interior of the cab.

Another feature of the invention consists in 20 the provision of a generally improved form of lamp in which the front openings are provided in a cover which is hinged at the top and is normally spring biased to close against the front end of the lamp casing, suitable means being provided for holding the cover in a raised or open position when full illumination of the interior of the locomotive cab is desired.

Other features and advantages of the invention will be more readily apparent from the following detailed description taken in connection with the accompanying drawings, in which—

Fig. 1 is a fragmentary sectional view of a locomotive cab equipped with a lamp constructed and arranged in accordance with this invention.

Fig. 2 is a top plan view of the lamp assembly shown in Fig. 1.

Fig. 3 is a longitudinal sectional view taken along the line 3—3 of Fig. 2.

Fig. 4 is a transverse sectional view taken substantially along the line 4—4 of Fig. 3.

Fig. 5 is a front view of the lamp showing the front openings through which concentrated beams of light are projected onto the different indicating instruments arranged on the back boiler head of the locomotive.

Fig. 6 is a view similar to Fig. 1 but showing a slight modification.

Fig. 7 is an end elevation of the lamp socket 50 adjusting means shown in Figs. 2 and 4.

Referring more particularly to the drawings 11 designates the interior of a locomotive cab equipped with the usual steam gauges and other indicating instruments appearing at 12, these instruments being usually arranged in the front

portion of the cab and carried by the back head 13 of the locomotive boiler 14. My improved lamp is arranged in the upper rear portion of the cab and is supported from the cab roof 15 by any suitable arrangement of supporting bolts 16, the lower ends of which are threadedly engaged with suitable portions 17 of the lamp casing 18.

The lamp casing shown in Figs. 1 to 5 inclusive includes side walls 19, a top wall 20, a bottom wall 21 and a rear wall 22, the front end of the casing being open and fitted with a flanged cover 24 in which the front light emitting openings 25 are provided. The size and location of each opening 25 is carefully predetermined so that the beam of light projecting through each opening from the light source 26 is centered on and substantially confined to the area occupied by one of the indicating instruments 12, thereby preventing excessive distribution of the projected light rays over portions of the boiler head 13 located outside the areas occupied by the instruments 12. The cover 24 is hingedly connected to the top wall 20 of the lamp casing by a hinge pin 27 about which the cover may be swung from the closed or full line position shown in Fig. 1 to the raised or open position indicated by the dotted lines in said figure. When the cover 24 is swung to the open or dotted line position shown in Fig. 1 it may be temporarily held in this position by engaging an edge portion of the cover with a spring-held cover supporting latch 28 which is fastened to the cab roof 15. As shown in Figs. 2 and 5 the cover 24 is normally biased to a closed position by a cover closing spring 26a encircling the hinge pin 27.

The light source 26 comprises an incandescent lamp having a plug portion 29 screwed into a socket 30 which is mounted in a neck extension 31 formed integral with one of the side walls 19 of the lamp casing. The socket 30 is preferably carried by a plate 32 which is fastened to the outer end of the neck extension 31 by bolts 33 and wing nuts 34. The plate 32 is preferably provided with elongated slots 35 for the passage of the bolts 33, this arrangement permitting the plate 32 and the lamp socket 30 to be raised and lowered when this is necessary to accurately position the filament of the incandescent lamp or light source 26.

The top and bottom walls 20 and 21 of the lamp casing are provided, adjacent the rear wall 22, with openings 20a and 21a. These openings communicate with the upper and lower ends of a curved ventilating passage 36a which is provided between the curved rear wall 22 and a similarly curved sheet metal plate 36, the ends of which are fastened to the walls 20 and 21 immediately in advance of the openings 20a and 21a. The end portions of plate 36 which lie opposite the openings 20a and 21a are solid but the central portion of said plate is preferably provided with a multiplicity of relatively small openings 38. When the lamp is in operation the heated air adjacent the incandescent bulb 26 passes into the ventilating passage 36a through the openings 38 and flows upwardly through said passage to the discharge opening 20a. At the same time cool air enters the passage 36a through the bottom opening 21a. This ventilating arrangement tends to prevent overheating of the bulb 26 and the adjacent wall portions of the lamp casing 18.

A light intercepting and controlling diaphragm 44 is arranged in the lamp casing 18 immedi-

ately in front of the incandescent bulb 26. As here shown this diaphragm comprises a rectangular plate provided with a central opening 45. The lower edge of the diaphragm is rolled 5 around and firmly secured to a rotary shaft 46, the end portions of which are journalled in bearing openings 47 provided in the side walls of the lamp casing 18. One end of shaft 46 projects beyond the adjacent side wall of the lamp casing and is fitted with a knurled wheel 48 by means of which shaft 46 may be turned to swing the diaphragm 44 from the vertical or full line position shown in Fig. 3 to the substantially horizontal or dotted line position. When the diaphragm 44 is swung to the upright or full line position shown in Fig. 3 it is releasably retained in such position by engagement with a spring latch 49 carried by the top wall 20 of the lamp casing. In this position of the diaphragm 44 10 the light from the bulb 26 is projected through the opening 45 so that practically none of this light falls on the inside wall portions of the lamp casing which are located between the diaphragm and the cover 24. This is a very desirable feature since reflection of light rays through the front openings 25 from inside wall portions of the lamp casing lying between these openings and the light source tends to increase the amount of scattered light which is projected 20 through said openings and thus interferes with the desired concentration of the light beams on the areas occupied by the indicating instruments 12.

In some cases it is desirable that a light filter 35 50 be arranged over the central opening 45 of the diaphragm 44. In order to provide for this the diaphragm may be provided with guide flanges 51 located at opposite sides of the opening 45 and with filter supporting lugs 53 located 40 adjacent the lower edge of said opening. This enables the filter 50 to be engaged beneath the guide flanges 51 with its lower edge resting on the supporting lugs 53. The use of a blue filter is recommended in cases where the effective illuminating capacity of the lamp must be reduced 45 to a very considerable degree to meet black-out conditions. It will be understood, however, that various other types of color filters may be used 50 dependent upon the extent to which the effective illuminating capacity of the lamp is to be reduced. In some cases it may be desirable to provide the diaphragm 44 with a light filter which transmits only ultra-violet light rays. For example, when such a light filter is used the indicating instruments 12 may be painted or coated 55 with some substance which is made luminescent by ultra-violet light rays. In this case the ultra-violet light rays transmitted through the color filter associated with the diaphragm 44 will render 60 the indicating instruments 12 visible with practically no illumination of the interior of the cab.

The diaphragm 44 is hingedly mounted so that it may be swung to the dotted line position shown 65 in Fig. 3 to facilitate placement and removal of the incandescent bulb 26. In this connection it will be noted that the bulb 26 must be inserted and removed through the front end of the lamp casing 18, there being sufficient room provided at 70 the rear end of the casing to provide for the manipulation of the bulb necessary to its insertion and removal from the lamp socket.

In Fig. 6 I have shown a slight modification in which the lamp casing comprises front and rear 75 sections A and B which are respectively bolted

to the front and rear surfaces of the rear cab wall C, the latter being provided with an opening C' for the transmission of light from the incandescent bulb 26 which is mounted in the rear lamp casing section B. In this case the diaphragm 44 is hingedly mounted in the front section A between the front cover 24 and the opening C'.

In both of the arrangements shown in Figs. 1 and 6 the lamp casing 18 is inclined so that the beams of light projected through the front openings 25 are directed downwardly against the indicating instruments 12 at such an angle that the reflected beams are directed downwardly toward the floor of the cab and therefore are not reflected directly into the eyes of the engineer.

Having thus described my invention, what I claim is:

A lamp casing provided with a front wall having openings therein, a source of light mounted in the rear portion of said casing at some dis-

tance from the front wall thereof, a rotatable shaft extending across the bottom wall of the casing immediately in front of said source of light and provided with an operating handle located exteriorly of said casing, a centrally apertured metal plate having its lower edge secured to said shaft so that said plate may be swung by appropriate rotation of said shaft to an upright position in front of said source of light or to a horizontal position extending forwardly from said shaft, said plate being provided with a central light transmitting aperture and being dimensioned so that the marginal edges thereof project laterally beyond the source of light into close proximity with the opposing walls of the casing when said plate is in its upright position and a spring catch secured to the top wall of said casing and adapted for engagement with the upper edge of said plate to hold the latter in its upright position.

FREDERICK W. BLANCHARD.
